SHOWCASE FOR TRANSPARENCIES OR
SIMILAR ARTICLES

Samuel A. Bishop, 527 Madison Ave.,
New York, N.Y. 10022

Filed Oct. 10, 1972, Ser. No. 295,994

Term of patent 14 years

Int. Cl. D6—04

U.S. Cl. D6—171

FIG. 3

FIG. 1

FIG. 2

FIG. 4

FIG. 6

FIG. 5

FIG. 8

FIG. 7

FIG. 1 is a front elevational view of a showcase for transparencies or similar articles showing my new design; FIG. 2 is a left side elevational view;

FIG. 3 is a top plan view;

FIG. 4 is a bottom plan view;

FIG. 5 is a rear elevational view;

FIG. 6 is a right side elevational view;

FIG. 7 is a rear elevational view of an alternative embodiment of a showcase showing my new design, wherein the front face is identical to that of FIG. 1; and

FIG. 8 is a left side elevational view of the embodiment shown in FIG. 7, the right side elevational view being a mirror image thereof.

I claim:

The ornamental design for a showcase for transparencies or similar articles, as shown and described.
